ATTORNEY

UNITED STATES PATENT OFFICE.

ANTHONY KENNEDY, OF DREXEL HILL, PENNSYLVANIA, ASSIGNOR TO THE MOLLAR COMPANY, OF PHILADELPHIA, PENNSYLVANIA, A CORPORATION OF NEW YORK.

SAFE OR VAULT WALL.

1,425,324.

Specification of Letters Patent. Patented Aug. 8, 1922.

Application filed November 15, 1918. Serial No. 262,636.

To all whom it may concern:

Be it known that I, ANTHONY KENNEDY, a citizen of the United States, residing at Drexel Hill, in the county of Delaware and State of Pennsylvania, have invented certain new and useful Improvements in Safe or Vault Walls, of which the following is a specification.

My invention relates to improvements in walls for safes or vaults which are constructed of manganese steel or other metal which cannot be machined and which are formed in separate wall plates or sections arranged edge to edge and secured together.

The object of my invention is to provide a wall structure of novel, simple and efficient construction, wherein the wall plates thereof are secured together by a novel means which will effectually prevent both lateral and edgewise displacement of the wall plates relatively to each other, and which will permit the parts to be assembled in a manner to draw the opposing edges of the plates together and retain them in close contact with each other.

With the above and related objects in view, my invention consists in the novel construction and combinations of parts herein-after fully described and particularly claimed.

In the accompanying drawings, illustrating my invention,

Figure 1 is a perspective view of a part of the meeting portions of two wall plates for a safe or vault, made in accordance with my invention, showing the studs thereon before they are riveted in the connecting plates.

Figure 2 is a similar view, including a series of connecting plates and showing the studs riveted in holes in the connecting plates.

Figure 3 is a view similar to Fig. 2, showing a continuous connecting plate instead of a series of connecting plates.

Figure 4 is a section, on line 4-4 of Fig. 2, showing the positions of the assembled parts before the studs are riveted in the holes in the connecting plate.

Figure 5 is a view similar to Fig. 4, after the riveting operation.

Referring to the drawings, 2 and 3 designate two adjacent wall plates, and 5 and 6 connecting plates for the wall plates 2 and 3.

The plates 2 and 3 are adapted to form parts of the top, bottom or side walls of a

safe or vault. The adjacent edge portions of the plates 2 and 3 abut against each other, and the edge portion of the plate 2 is provided with a central, longitudinally-extending rib 7 which is fitted into a central, longitudinally-extending groove 8 in the adjacent edge portion of the plate 3. The plates 2 and 3 are usually formed of unmachinable metal, such as manganese steel, and the edge portions thereof are finished to fit against each other by suitable grinding operations, well known to persons skilled in this art.

The wall plates 2 and 3 are provided with projecting pins or studs 9 and 10, respectively, arranged at intervals along the meeting edge portions of the plates. These studs 9 and 10 are formed or cast integral with the plates 2 and 3, and the studs 9 and 10 project from the inner faces of the plates 2 and 3.

Arranged against the inner faces of the wall plates 2 and 3 are a number of suitably spaced connecting plates 5, as shown in Figs. 2, 4 and 5, which cross the joint between the plates 2 and 3, and which may be formed of any suitable material, preferably machinable metal. The studs 9 of the plate 2 are paired with the studs 10 of the plate 3, and a connecting plate 5 is provided for each pair of studs. The connecting plates 5 are provided with counter-sunk holes 11 and 12 into which the studs 9 and 10 extend, as clearly shown in Fig. 4.

In assembling the parts, the rib 7 of the plate 2 is entered into the groove 8 of the plate 3, and the adjacent edge portions of the plates 2 and 3 are brought into contact with each other, as clearly shown in the drawings. The connecting plates 5 are then placed against the inner faces of the wall plates 2 and 3, as shown in Fig. 2, with the studs 9 and 10 projecting through the holes 11 and 12, as shown in Fig. 4. This being done, the projecting ends of the studs 9 and 10 are riveted in the counter-sunk holes 11 and 12 of the plates 5, as shown in Figs. 2 and 5. During the riveting operation, the blows are struck against the ends of the studs 9 and 10, in the directions of the arrows, shown in Figs. 4 and 5, thereby displacing the studs 9 and 10 toward each other and thus drawing the abutting edge portions of the plates 2 and 3 into close contact with each other through the medium of the studs 9 and 10 and the connecting plates 5, and forming a very tight joint between the wall plates 2 and 3.

105
110

In Fig. 3 of the drawings, I have shown one continuous connecting plate 6 instead of the series of plates 5, shown in Fig. 2. The continuous connecting plate 6 extends the full length of the joint between the wall plates 2 and 3 and it is provided with spaced holes in which all the studs 9 and 10 are riveted, as a means of securing it to the wall plates.

10. In order that the full thickness of the connecting plates 2 and 3 shall not extend into the interior of the safe or vault beyond the plane of the inner faces of the main bodies of the wall plates, I provide the wall plates 2 and 3 with offset portions 13 and 14 in the region of the joint between the plates for the reception of portions of the connecting plates 5 and 6 as clearly shown in the drawings. When the parts are assembled, as hereinbefore described, a joint between the wall plates 2 and 3 is provided which is strong and durable and which cannot be opened from the outside of the safe or vault; and a joint is provided in which relative lateral 25 and edgewise displacement of the wall plates

2 and 3 is prevented by the combined action of the connecting plates 5, the studs 9 and 10, the rib 7 and the walls of the groove 8, and in which the abutting edge portions of the wall plates are held firmly together and in close contact with each other.

I claim:—

A safe or vault wall comprising two wall plates formed of unmachinable metal and having contacting edge portions, the edge portion of one plate having a longitudinally extending rib projecting into a longitudinally extending groove in the edge portion of the other plate and preventing lateral separation of the plates, and a connecting plate arranged against the inner surfaces of the wall plates and crossing the joint between them, the connecting plate being secured to the wall plates by studs formed integral with the wall plates and riveted in holes in the connecting plate and preventing edgewise separation of the wall plates.

In testimony whereof I affix my signature hereto.

ANTHONY KENNEDY.
